(57) **CLAIM**

The ornamental design for a beaded fiber cement panel, as shown and described.

DESCRIPTION

FIG. 1 is a front perspective view of a beaded fiber cement panel in accordance with invention;

FIG. 2 is an enlarged view of a middle boxed portion of the beaded fiber cement panel shown in FIG. 1;

FIG. 3 is an enlarged view of a top boxed portion of the beaded fiber cement panel shown in FIG. 1;

FIG. 4 is an enlarged view of a bottom boxed portion of the beaded fiber cement panel shown in FIG. 1;

FIG. 5 is a front elevation view of the beaded fiber cement panel shown in FIG. 1;

FIG. 6 is a rear view of the beaded fiber cement panel shown in FIG. 1;

FIG. 7 is side view of the beaded fiber cement panel shown in FIG. 1;

FIG. 8 is an enlarged view of a middle boxed portion of the beaded fiber cement panel shown in FIG. 4;

FIG. 9 is an enlarged view of a top boxed portion of the beaded fiber cement panel shown in FIG. 4;

FIG. 10 is an enlarged view of a bottom boxed portion of the beaded fiber cement panel shown in FIG. 4;

FIG. 11 is top view of the beaded fiber cement panel shown in FIG. 1; and,

FIG. 12 is a bottom view of the beaded fiber cement panel shown in FIG. 1.

For FIGS. 1-12, broken lines are for illustrative purposes only, showing the environment, and form no part of the claimed design.
